UNITED STATES PATENT OFFICE.

JAMES WILLIAM WALKER, JR., OF WINSTON-SALEM, NORTH CAROLINA.

GAS GENERATING AND HEATING APPARATUS.

1,325,062.

Specification of Letters Patent. Patented Dec. 16, 1919.

Application filed March 6, 1918, Serial No. 220,839.

Renewed November 6, 1919. Serial No. 336,154.

To all whom it may concern:

Be it known that I, JAMES WILLIAM WALKER, Jr., a citizen of the United States, residing at 509 Slade street, Winston-Salem, 5 North Carolina, U. S. A., have invented certain new and useful Improvements in Gas Generating and Heating Apparatus; and I do hereby declare that the following is a full, clear, and exact description of the 10 same.

The present invention relates to an improved gas generating apparatus, especially designed to generate a gas, preferably from petroleum, which may be utilized for heating and illuminating purposes, and which 15 may also be used for other purposes.

The invention has for its primary object to produce a gas from petroleum or the like which will have greater heating properties 20 than that now obtained.

A further object is to produce the maximum amount of heat from petroleum by adding or combining with the petroleum vapors oxygen-containing vapors or gases, 25 such for instance as the gas derived by heating chlorate of potassium, etc.

Another object is to provide a gas mixture that will not clog or obstruct a burner, if used for heating, by the accumulation 30 of carbon, by causing the carbon and its by-products to pass through the burner openings in the form of a carbon-dioxid gas by reason of its splitting the steam and combining the oxygen of such steam with the 35 heated carbon.

The invention consists in mixing the petroleum vapor with oxygen or other gaseous substance that will increase the heating properties of the petroleum gas preferably 40 by first heating them independently to the point where they have about an equal volatility, when they will readily combine. These gases may also be produced in a common chamber and heated sufficiently to 45 unite. But this is facilitated by breaking up the superheated gases by means of strands of metal in the shape of netting, or by means of a plurality of mineral strands that will not melt under the intense heat. 50 Thus the gas derived from the petroleum will more easily mix or unite with the oxygen gas.

In order to better understand the invention, the accompanying drawings disclosing

a heating apparatus constructed in accordance with the invention will be described.

Figure 1 is a perspective view of a retort and burner, disclosing two gas heating chambers.

Fig. 2 is a perspective view of a reservoir 60 for holding petroleum and water to be used in connection with the apparatus shown in Fig. 1.

Fig. 3 is a perspective view of a retort and burner of similar construction to that 65 disclosed in Fig. 1, but modified in as much as a supplementary gas heating chamber is provided.

Fig. 4 is a cross section on line A—A of 70 Fig. 1.

Like numerals of reference indicate corresponding parts in each figure.

In the drawings, 1 and 2 are horizontal tubes preferably parallel in relation to one another, and forming independent gas heating chambers, said tubes being secured at one end to a mixing chamber 3. A vertical pipe 4 is secured at one end to said mixing chamber 3, and 5 is a horizontal tube, parallel with said tubes 1 and 2, and connected 75 at one end to said vertical tube 4. One or more holes 6 are provided in the upper surface of said tube 5 to provide suitable burner openings. A tray 7 is provided below said tube 5 and is adapted to support the apparatus by means of a vertical leg 8 to which is secured one end of the tube 5. The tray 7 is provided with a plurality of perforations 9.

At one end of each of the tubes 1 and 2 90 is provided a well 10, and 11 and 12 are supply pipes leading to said tubes 1 and 2 from the tanks 13 and 14 respectively. The tubes 1 and 2, the mixing chamber 3, the pipe 4 and the retort pipe 5 are filled with 95 a packing of coarse sand 15 (preferably a mineral sand) or with strands of asbestos, which will serve as a wick and cause an even feeding of the gas to the burner openings 6. A metallic netting 16 is also provided inside said tubes to break up the superheated gases and cause them to mix, thus facilitating their union.

A baffle plate 17 is provided above each burner opening 6, to spread out or deflect 105 the flames as the case requires, said plates being secured to the tubes 1 and 2 in any suitable way.

The tank or reservoir 13 is preferably adapted to contain petroleum and is provided with a receiving tube 18 and funnel 19. This tube 18 is disposed in line with and connected to the adjacent portion of the supply pipe 11, and communicates in some suitable manner (not shown) at its lower end with the interior of the tank, so that the petroleum in the latter enters said tube 18 by way of such communication and then passes into the pipe 11; and in this respect it is similar to the construction shown and described in my prior application, Serial No. 217,696, filed February 16, 1918, to which reference may be had.

The tank or reservoir 14 is preferably provided with a strainer, and adapted to receive water.

Controlling valves 20 are provided on the pipes 11 and 12, as illustrated in Fig. 2.

The operation of the invention will be clearly understood from the following: The valves 20 are turned on and the asbestos waste in the tray 7 having been ignited, will heat the retort 5 and tubes 1 and 2. The petroleum enters the heated tube or chamber simultaneously with the water in the tube or chamber 2, and both are heated so that they will be turned into gas. The gases formed then pass into the mixing chamber 3 where they unite or combine and then pass through the burner openings 6. It may be preferable at first, to start with the petroleum in order to properly heat up the tubes 1 and 2 and then to gradually turn on the valve controlling the water supply.

By combining a proper proportion of oxygen with the carbon, an intense heat will be obtained with a minimum of petroleum.

In the modification disclosed in Fig. 3 of the drawings a supplementary gas heating chamber 21 is provided consisting of a tube secured at one end to the mixing chamber 3 in which chamber may be provided a substance such as chlorate of potassium which will be simultaneously heated with the petroleum and water, thereby increasing the amount of oxygen supplied.

It will be readily understood that without departing from the spirit of the invention one gas heating chamber may be used, which could be filled or supplied with oxygen, or with any other substance having similar properties where it will mix with the petroleum and thereby dispense with the mixing chamber 3.

It may also be stated that the apparatus herein described may be altered without departing from the spirit of the invention, and it is here illustrated to better understand the process of increasing the heating properties of petroleum gas or the like.

It will be readily seen that a gas of high heating and illuminating properties will be

obtained, as well as a gas particularly cheap and manufactured at a minimum cost. This gas may also be employed, as already mentioned, for various other purposes in which gas is used. An important feature of the gas is that the carbon being so treated will not clog or obstruct as it usually happens especially in ordinary petroleum gas.

What I claim is:

1. An apparatus for producing and burning gas, comprising a pair of horizontal tubular heating chambers arranged side by side in parallel relation, a hydrocarbon supply tank connected directly to one end of one of said chambers, a water supply tank connected directly to the corresponding end of the other chamber, a mixing chamber into which both chambers directly open at the other end thereof, a single perforated horizontal burner tube located below and substantially midway between said heating chambers, a vertical pipe leading from said mixing chamber to the adjacent end of said burner tube, and a tray disposed beneath said burner tube and connected to the same to support said chambers and tube, said tray being adapted to contain an inflammable substance for initially heating said burner tube and heating chambers when ignited, so as to vaporize the hydrocarbon and water.

2. An apparatus for producing and burning gas, comprising a pair of horizontal tubular heating chambers arranged adjacent each other in spaced, parallel relation, a hydrocarbon supply tank connected with one end of one of said chambers, a water supply tank connected with the corresponding end of the other chamber, an intermediate tubular heating chamber between and parallel with the first-named heating chambers to contain a vaporizable substance adapted to give off oxygen when heated, a mixing chamber into which all three heating chambers directly open, a perforated horizontal burner tube located below said heating chambers, a vertical pipe connection between said mixing chamber and the adjacent end of said burner tube, and a tray disposed beneath said burner tube and connected to the same to support said chambers and tube, said tray being adapted to contain an inflammable substance for initially heating said burner tube and heating chambers when ignited, so as to heat the hydrocarbon and water and the said vaporizable substance.

Signed at Montreal, Quebec, Canada, this second day of March, 1918.

JAMES WILLIAM WALKER, JR.
